F. LAIBACH

LOOKOUT OR DOOR PEEP

Filed May 21, 1919

Inventor
Franz Laibach
By his Attorney
Oscar Geier

UNITED STATES PATENT OFFICE.

FRANZ LAIBACH, OF NEW YORK, N. Y.

LOOKOUT OR DOOR PEEP.

Application filed May 21, 1919. Serial No. 298,731.

To all whom it may concern:

Be it known that I, FRANZ LAIBACH, a citizen of the United States, residing at New York, county of New York, and State 5 of New York, have invented certain new and useful Improvements in Lookouts or Door Peeps, of which the following is a specification.

This invention relates to an improved 10 lookout or door peep adapted to be applied to the doors of dwellings, lodge rooms, or the like to permit of visual examination by the occupants of any person desiring admission before the door is opened, the invention being an improvement on that disclosed and 15 claimed in a previous patent granted to me on Dec. 10, 1918, under No. 1,287,349.

The present invention has for one object 20 to improve the means for securing the door peep in place.

Another object is broadly to widen the range of vision of the door peep when applied to a door of considerable thickness.

For further comprehension of the invention, and of the objects and advantages 25 thereof, reference will be had to the following description and accompanying drawings, and to the appended claims in which the various novel features of the invention are 30 more particularly set forth.

Figure 1 of the drawings is a front view of a door peep constructed according to my invention.

Figure 2 is an axial sectional view thereof, showing it in position on a door.

Figure 3 is a horizontal axial sectional view.

Figure 4 is a transverse section on the line 4-4 of Fig. 3.

Referring now to Figs. 1 to 4 1 indicates a door of ordinary construction such as is used in dwellings, lodge rooms or the like. This door is formed with an aperture 2 to receive the door peep which here comprises 45 a tube 3 having soldered or otherwise secured on one end a sleeve-like extension 4 which fits snugly in the aperture 2.

The opposite end of the tube 3, which extends inwardly into the room or apartment, is formed with a cupped disc 6 whose flange projects over and localizes a ring 7 spaced between the disc and the inner face of the door, the purpose of this ring being presently set forth.

55 The extreme inner end of the tube 3 has

soldered or otherwise fixed therein a flaring eye-piece 8 which carries a lens 9. A second lens 10 is carried at the opposite end of the door peep, being mounted in a short cylindrical member 11 which projects into the sleeve 4 at one end and at its opposite end into a cylindrical flange 12 projecting from a circular plate 13 upon the outer face of the door. This plate 13 may have soldered on its face a ring 14 holding a plain glass disc 15 which covers and protects the lens 10.

The lenses 9 and 10 are constructed in a manner known to those skilled in the art, to widen the range of vision from the eye piece 70 so as to enable the occupant to obtain a comprehensive view through the door peep. In order to further increase the range of vision so as to enable a person out of direct alinement with the eye peep, or a number 75 of persons, to be examined the lenses are secured in rings 16 mounted on vertical pivots 17 and are connected together by a telescopic strip made up of two parts 18, 18' and which is secured to one side of each of 80 such lenses and extends through the tube 3 close to the side thereof, and may be extended or constructed according to the distance the lenses are spaced apart, the two parts of the strip engaging one another with 85 sufficient frictional hold to move the shutters but may be moved upon one another by hand for adjustment.

Secured to one of the pivots 17 is a projecting handle 19 and it will be apparent 90 that by manipulation of this handle the lenses may be swung on their pivots to face at an angle toward either side of the door.

The device is held in position by means of screws 20 which pass freely through suitable openings in the disc 6 and door, and through tapped openings in the plate 13 and ring 14 and have nuts 21 threaded on their ends. The ring 7, before mentioned, acts as a spacer and rings of different axial 100 width, or a plurality of rings, may be employed according to the thickness of the door in which the device is to be placed.

In front of the lens 9 I provide a pair of shutters 23 and 24 which are hinged on 105 a common axis as at 25 on the disc 6 and have operating handles 23' and 24' thereon, the tube 3 being slotted to receive the shutters. The shutter 23 is solid and the shutter 24 is provided with a slot 26 for a peep 110

hole. The upward movement of both shutters is limited by a lug 27 on the shutter 23 which engages the wall of tube 3 when the shutter is moved up. In order to hold the 5 shutter 24 in position when the shutter 23 is raised the handle 24' of the former has an integral spring clip or finger 24* which projects over and engages yieldingly a projection 24^b on the disc 6.

10 It will be understood of course that any of the shutter constructions here shown may be combined with any of the tube or mounting constructions and that plain glasses at both ends or a single lens at the inner end 15 may also be employed as desired.

It is also to be understood that the lighting fixture shown in my previous patent above referred to may be employed in connection with the improved look out herein 20 set forth.

It is obvious that the movable lenses, not only may be used as stationary lenses and are not only adaptable for doors or the like, but may be used for other purposes in the 25 art demanding an oblique vision.

Having thus described my invention and set forth the manner of its use, what I claim as new and desire to secure by Letters Patent, is:—

30 1. A tube having angularly adjustable lenses therein, and means for supporting

said tube and means for adjusting said lenses in unison.

2. In a look-out, a tube having an angularly adjustable lens at each opposite end thereof, means for securing said tube in a door, and means for adjusting said lenses in unison. 35

3. In a look-out, an adjustable tube having angularly adjustable lenses, means for securing said tube to a support and means for adjusting said lenses in unison, said means including an extendible link passing through the tube and connected to the said lenses so that the lenses will co-operate 40 through a limited angle of movement, or until the axis of each, fails to intersect the other. 45

4. In a look-out, a tube having an angularly adjustable lens at each opposite end thereof, means for securing said tube in a door, and means for adjusting said lenses in unison, said means including a link passing through the tube at one side thereof, and connected at the opposite ends to the said lenses, so that the two lenses will co-operate 50 through a limited angle of movement, or until the axis of each fails to intersect the other. 55

In testimony whereof I have affixed my 60 signature.

FRANZ LAIBACH.
